CLAIM

The ornamental design for a tape dispenser with relieved side, as shown and described.

DESCRIPTION

This application is a design patent application, which claims priority from U.S. Patent Application Ser. No. 10/232,236, filed Aug. 29, 2002 in the United States Patent and Trademark Office.

FIG. 1 is a perspective view of a tape dispenser with relieved side showing my new design;

FIG. 2 is a top plan view;

FIG. 3 is a left side elevational view;

FIG. 4 is a bottom plan view;

FIG. 5 is a front elevational view;

FIG. 6 is a rear elevational view;

FIG. 7 is a perspective view of a second embodiment of my design of FIG. 1;

FIG. 8 is a top plan view of FIG. 7;

FIG. 9 is a left side elevational view of FIG. 7;

FIG. 10 is a bottom plan view of FIG. 7;

FIG. 11 is a front elevational view of FIG. 7;

FIG. 12 is a rear elevational view of FIG. 7;

FIG. 13 is a perspective view of a third embodiment of my design of FIG. 1;

FIG. 14 is a top plan view of FIG. 13;

FIG. 15 is a left side elevational view of FIG. 13;

FIG. 16 is a bottom plan view of FIG. 13;

FIG. 17 is a front elevational view of FIG. 13; and,

FIG. 18 is a rear elevational view of FIG. 13.
